His Attorney.

UNITED STATES PATENT OFFICE

2,207,572

ELECTROMAGNET

Edgar H. Ayers, Schenectady, N. Y., assignor to
General Electric Company, a corporation of
New York

Application August 25, 1939, Serial No. 291,377

3 Claims. (Cl. 175—21)

My invention relates to electromagnets and has for its object a simple and low cost electromagnet structure.

In carrying out my invention, I utilize a strip 5 of non-magnetic spring material which is secured to one of the magnetic core members so as to provide an air gap between this member and another magnet core member, this strip being also arranged to position relatively the magnet core members with respect to each other and also engage and hold a magnet coil on one of said core members in a predetermined position.

For a more complete understanding of my invention, reference should be had to the accompanying drawing in which Fig. 1 is a plan view of a relay embodying my invention; Fig. 2 is a side elevation view of the relay shown in Fig. 1 while Fig. 3 is an exploded view showing various parts in perspective.

20 Referring to the drawing, I have shown my invention in one form as applied to a relay 10 which is enclosed in a metallic casing 11 and has connected thereto a supply transformer 12. The relay comprises an L-shaped magnet core member 13, which, as shown, is laminated and on one leg 13a of which is mounted a magnet coil 14. Cooperating with this core member 13 is a straight core member 15, shown as unlaminated, which forms a third leg of a magnet core. One 25 end of the member 15 is clamped securely to the end of the core leg 13b by means of a screw 16 extending through the member 15 into engagement with a nut 17 secured in a slot in the end of the leg 13b.

30 Between the leg 13b and the member 15 is clamped a thin strip 18 made of a suitable non-magnetic spring material such as bronze. One function of this strip is to provide an air gap in the magnetic circuit, which it introduces between the two magnet core members by reason of its own non-magnetic properties and thickness. The strip is secured to the magnet member 15, as by rivets 19, and it is provided with a forked end 20 bent laterally with respect to the 35 member 15, the two prongs of the fork embracing the end of the core leg 13a at the outer end of the coil 14 when the magnet member 15 is secured in place. The end 20 is furthermore permanently shaped so as to apply a spring force 40 to the outer end of the coil 14 and thereby hold it securely in position on the core leg 13a with the other or inner end of the coil pressed against the leg 13b. Also the projections on the end 20, by reason of their engagement with the core member 13a, hold the magnet member 15 against ro-

tary or pivotal displacement about the screw 16 in the event that the screw becomes loosened.

The relay device further embodies a movable member 21 made of unlaminated magnet material which constitutes an armature. This member 21 is provided with a central aperture 22 to receive a projection 23 on the member 15. The member 21 is also provided with side notches 24 and 25 which receive the projections 26 and 27 on the member 15. Also secured to the outer face of the armature 21 is a weight 28 having a projection 29 on its lower side which extends through the aperture 30 in the projection 23 and thereby secures the armature 21 on the core member 15. A flexible contact arm 31 is secured to the outside of the weight 28, the function of the weight being to prevent rebound of the contact arm when it strikes the stationary contact 31a. As shown, the parts 21, 28, 31 are secured together by means of a screw 32. A tension 20 spring 33 is provided having its ends connected to the projection 29 and the screw 16 so as to bias the armature 21 and contact arm 31 to their unattracted positions.

While I have shown a particular embodiment 25 of my invention, it will be understood, of course, that I do not wish to be limited thereto, since many modifications may be made, and I, therefore, contemplate by the appended claims to cover any such modifications as fall within the 30 true spirit and scope of my invention.

What I claim as new and desire to secure by Letters Patent of the United States, is:

1. An electromagnet comprising two core members, means securing a first end of one of said core members to a first end of the other of said core members so that the opposite ends of said core members are spaced apart to form two magnet poles, a coil on one of said core members for producing a flux between said poles passing through said core members, and a member made of non-magnetic material between said first ends to form an air gap between them and secured to one of said core members, said non-magnetic member having a laterally extending portion engaging the other end of the other core member to secure said core members in a predetermined relation with respect to each other and engaging the outer end of said coil to hold said coil in position.

2. An electromagnet comprising an L-shaped core member and a second core member, means securing a first end of said second core member to a first end of said L-shaped core member so that the other ends of said core members are spaced

50

55

- apart to form two magnet poles, a coil on said L-shaped member, and a member made of non-magnetic spring material between said first ends of said members to form an air gap between them and secure to said second core member, said non-magnetic member having a laterally extending portion engaging said other end of said L-shaped member to secure said core members in a predetermined relation with respect to each other and engaging the outer end of said coil to hold said coil in position on said L-shaped member.
3. An electromagnet comprising an L-shaped core member and a straight core member, a single screw securing one end of said straight core

member to one end of said L-shaped core member, a coil on one arm of said L-shaped member having an inner end engaging the other arm of said member, and a relatively thin elongated member made of non-magnetic spring material having one end between said members to form an air gap between them and secured to said straight core member, said member having a laterally extending forked portion adjacent the other end of said straight core member embracing the other end of said L-shaped member to secure said ends in a predetermined relation with respect to each other and engaging the outer end of said coil to hold said coil against said other arm.
